PORTABLE ELECTRIC LIGHT.

1,360,477.

Specification of Letters Patent. Patented Nov. 30, 1920.

Application filed November 12, 1919. Serial No. 337,541.

To all whom it may concern:

Be it known that I, CHARLES WACHTEL, a citizen of the United States, and resident of Jamaica, in the borough and county of 5 Queens, Long Island, in the State of New York, have invented certain new and useful Improvements in Portable Electric Lights, of which the following is a specification.

This invention relates to improvements in 10 portable, self-contained electric lighting devices.

The invention has for one of its objects the provision of a portable electric lamp having a metallic casing forming part of the 15 lamp circuit, the parts of the lamp being so constructed and arranged that accidental closure of the circuit by contact of the lamp parts with metallic tools or objects is impossible.

20 A further important object of the invention is the provision of a portable electric lighting device comprising a casing containing a removable battery or dry cell, a lamp supported at one end of the casing, normally 25 open circuit-closing means interposed between the lamp and the adjacent battery terminal adapted to connect said battery terminal with one terminal of the lamp, and means including the casing forming an electrical connection between the other lamp 30 terminal and the battery terminal at the opposite end of the casing.

Another object of the invention is to provide circuit-closing means for a portable 35 electric lighting device, embodying stationary and movable contacts and a manually operable controlling device or push button engaging said movable contact and adapted to close the circuit when forced inwardly, 40 said controlling device being also laterally shiftable when pushed inwardly to move the same into engagement with an abutment for locking the movable contact in circuit-closing position.

45 Another object of the invention is to provide a portable electric lighting device having a tubular body portion, a battery in the body portion, a closure cap for one end of the body having a frictional slip connection 50 with the body portion, and a combined reflector, lamp socket and lens support having a frictional slip connection with the other end of the body portion.

Another important object of the invention 55 is the provision of a lighting device

comprising a tubular metallic shell having a battery removably contained therein, a detachable metallic closure cap for one end of the shell having a coiled spring yieldably engaging the adjacent terminal of the battery, a detachable metallic combined lamp socket, reflector and lens support held to the other end of the shell, a removable insulating block interposed between the lamp and the adjacent battery terminal and carrying 60 normally spaced contacts engaging the lamp and battery terminals, and a controller extending through the casing and insulated from the contacts on said blocks adapted to move one of said contacts into engagement 65 with the other.

In the drawings, Figure 1 is a longitudinal sectional view of the device;

Fig. 2 a side elevation thereof showing the parts disconnected from each other; 75

Fig. 3 a transverse section on the line III—III of Fig. 1;

Fig. 4 a fragmentary longitudinal section showing the finger piece locked in its laterally shifted circuit-closing position; 80 and Fig. 5 an enlarged sectional view of the push button.

Referring to the various parts by numerals, 1 designates the tubular metallic shell or casing in which the usual dry battery 2 is 85 removably held. The casing 1 is pressed outwardly adjacent each end to form external circumferentially extending shoulders 3 and 4, and the end portions of the casing are preferably tapered from the 90 shoulders 3 and 4 toward the ends of the casing as shown. The battery 2 has the usual terminals 5 and 6 at opposite ends thereof and the end of the casing 1 adjacent terminal 6 is closed by a removable 95 metal closure cap 7. The casing and cap are preferably formed of thin-gage sheet metal so as to be slightly resilient and insure a tight frictional slip connection between the cap and casing. The cap 7 is preferably 100 formed with knurled portions 8 and 9 to facilitate removal of the cap, and a compressible coiled spring 10 is held to the interior of the cap and is adapted to yieldably engage the battery terminal 6 to electrically 105 connect the cap with said terminal.

The casing 1 is pressed inwardly to form an internal circumferential shoulder 11 intermediate the shoulder 3 and the adjacent end of the battery 2, and is formed with a key 110

slot 12 therein extending longitudinally of the casing between said shoulders 3 and 11. Diametrically opposite the key slot 12 the casing is pressed inwardly to form an internal 5 rib or projection 13. A removable disk or block 14 of suitable insulating material is seated in the casing against the shoulder 11, said block having a notch 15 in one edge to receive rib 13 to hold the block against rotation. The disk or block 14 is slotted or cut away at 16 directly opposite the notch 15, the open end of the slot 16 registering with the key slot 12 in the casing. A metallic sleeve 17 extends through the center of the 10 block 14 and a metallic contact pin 18 is tapped transversely through the block from the inner end of slot 16, the outer end of said pin projecting into slot 16 and the inner end thereof engaging in one wall of the sleeve 15. A contact 19 in the form of a U-shaped 15 metal strip is held to the inner side of the block 14 by a suitable screw 20 extending through one end thereof. The battery terminal 5 is held in firm engagement with the contact 19 by the spring 10 in closure cap 7. A yieldable contact or spring-pressed metal plunger 21 is slidably held in the sleeve 17, said plunger being normally forced outwardly by a coiled spring 22 and having a 20 stop pin 23 tapped through its inner end. A resilient bridging member 24 is adapted to electrically connect the contacts 19 and 21 through the pin 18 and sleeve 17. The bridging member is preferably formed integrally 25 with the contact 19 for convenience in manufacture and assembly, the free end of the metal strip of which contact 19 is formed being passed through slot 16 to the opposite side of block 14 and doubled upon itself to 30 form a yieldable or compressible member normally out of engagement with the end of pin 18 but adapted to be pressed inwardly firmly against the outer end of the pin.

A combined reflector, lens support and 35 lamp socket is detachably held to the end of the casing opposite the closure cap 7, the reflector portion 25 thereof being formed with an integral annular flange 26 frictionally embracing the adjacent tapered end 40 portion of the casing 1. A threaded lamp socket 27 is formed integrally with the reflector 25, and an incandescent electric lamp 28 having the usual threaded metallic terminal sleeve 29 is supported in said socket 45 with its other terminal 30 in engagement with the yieldable contact plunger 21. The outer edge of the reflector 25 is rolled backwardly to form an integral external annular flange 31 formed at opposite sides with inclined bayonet slots 32 in which are adapted 50 to engage a pair of nipples or projections 33 formed on the interior of a lens-clamping ring 34 adapted to detachably hold a lens 35 against the outer edge or rim of the reflector. 55 The flange 26 is preferably formed with a

knurled shoulder 36 and the ring 34 is also provided with a knurled shoulder 37.

It will be observed that the lamp terminal 27 is connected at all times with the battery terminal 6 through the reflector, flange 26, 70 casing 1, cap 7 and spring 10, while lamp terminal 30 is normally disconnected from battery terminal 5. The terminals 5 and 30 are completely inclosed within the casing so that it is impossible to complete the circuit through accidental bridging of these terminals by metal tools or other objects. The circuit is adapted to be manually closed by operating a push button or finger piece 75 80 38 extending through the key slot 12 in casing 1. The push button has a portion 39 normally extending through the large part of the key slot and a reduced shank portion 40 normally located exteriorly of the casing 1. The portion 39 is formed with a circumferential flange 41 at its inner end adapted to engage the inner side of the casing to limit the outward movement of the button, and the outer edge of the portion 39 adjacent the reduced shank 40 is preferably 85 rounded. The button is normally forced outwardly by a flat spring 42 held to the inner side of the casing by suitable rivets 43. The spring 42 is formed with a short longitudinal slot 44 through which 90 a stud, pin or projection 45 of insulating material extends, said stud being held to the inner end of the button 38 and loosely engaging the bridging member or plate 24. The slot 44 is preferably of such length that 95 when the portion 39 of the button is engaged in the large portion of the key slot the pin 45 will engage the outer end of the slot, thus preventing movement of the button toward the shoulder 3 when the button is depressed. 100

It will be obvious that by pressing the button inwardly the bridging member 24 will be moved to circuit-closing position, and that when the pressure on the button is relieved the spring 42 will force the button outwardly, whereupon the resilient bridging member 24 will move out of engagement with pin 18 and the circuit will be broken. If it be desired to have the lamp burn continuously, the bridging member 24 may be 110 locked in circuit-closing position by pressing the button inwardly and then shifting the button laterally to engage the reduced shank portion 40 in the narrow portion of the key slot. This lateral movement of the button 115 will cause the abutment formed by the outer end of portion 39 of the button to engage under the abutments formed by the wall of the casing at the sides of the narrow portion of the key slot, thus holding the button depressed and maintaining the circuit closed after pressure of the thumb or finger on the button is relieved.

By providing a removable circuit controller within the casing it will be seen that 120 125 130

in the event of a battery sticking in the casing the lamp may be readily dismantled to permit access to the battery to drive the same out of the casing. It will be observed also 5 that the lens, reflector and lamp may be readily removed as a unit.

What I claim is:

1. A device of the class set forth comprising a casing open at both ends, a battery 10 movably held in the casing, a closure cap for one end of the casing having a frictional slip connection therewith, and a combined lamp socket, lens support and reflector provided with an annular flange having a frictional 15 slip connection with the opposite end of the casing and removable as a unit therefrom.

2. A device of the class set forth comprising a tubular metallic casing having tapered end portions, a battery removably held in the 20 casing, a closure cap frictionally embracing one tapered end portion of the casing, a combined reflector and lens support formed of sheet metal and provided with an annular flange frictionally embracing the opposite 25 tapered end portion of the casing, and a lamp and lens carried by the reflector and lens support.

3. A device of the class set forth comprising a metallic casing open at both ends, a 30 battery removably held in the casing, a detachable closure for one end of the casing, a metallic reflector having a lens-supporting end and an annular flange frictionally embracing the other end of the casing and a 35 threaded tubular lamp socket portion concentric with said flange, a lamp in said socket, a lens, and a lens-holding ring detachably held to the outer end of the reflector and clamping the lens against the lens-support- 40 ing end of the reflector.

4. A device of the class described comprising a metallic shell open at both ends, a battery therein having terminals at opposite ends thereof, a metallic closure having a slip 45 connection with one end of the casing, yieldable means carried by said closure electrically connecting the closure with the adjacent terminal of the battery, a metallic combined reflector and lamp socket having a 50 tubular extension at the convex side thereof surrounding the lamp socket portion thereof and frictionally engaging the other end of the shell to detachably hold the same to the shell, a lamp in the socket, and circuit-clos- 55 ing means adapted to electrically connect one terminal of the lamp with the adjacent battery terminal, the other lamp terminal being connected with the metallic shell through the combined reflector and lamp socket and 60 the tubular extension thereof.

5. A device of the class described comprising a metallic shell open at both ends, a battery therein having terminals at opposite ends thereof, a metallic closure having a slip 65 connection with one end of the casing, yield-

able means carried by said closure electrically connecting the closure with the adjacent terminal of the battery, a metallic combined reflector and lamp socket having a tubular extension at the convex side thereof 70 frictionally engaging the other end of the shell to detachably hold the same to the shell, a lamp in the socket, a block of insulating material interposed between the battery and lamp, contacts carried by said block 75 engaging adjacent battery and lamp terminals, and means operable from the exterior of the shell for electrically connecting said contacts, the other lamp terminal being electrically connected with the shell through the 80 reflector and its tubular extension.

6. A device of the class described comprising a metallic shell open at both ends, a battery therein having terminals at opposite ends thereof, a metallic closure having a slip 85 connection with one end of the casing, yieldable means carried by said closure electrically connecting the closure with the adjacent terminal of the battery, a metallic combined reflector and lamp socket having a 90 tubular extension frictionally engaging the other end of the shell to detachably hold the same to the shell and electrically connect the lamp socket portion thereof with the shell, a lamp in the socket, a block of insulating material 95 removably held in the shell between the lamp and battery, contacts carried by said block engaging adjacent battery and lamp terminals, a resilient bridging member carried by one of said contacts and normally 100 spaced from the other contact and adapted to be shifted into engagement therewith, and a finger piece extending through the shell and operable to force said bridging member into circuit-closing position. 105

7. A device of the class described comprising a metallic casing having a key slot therein, a battery in the casing having a terminal at its outer end electrically connected with the casing and having a terminal at its inner end, a lamp having one terminal spaced from the inner battery terminal and a terminal electrically connected with the casing, a block of insulating material interposed between the spaced battery 110 and lamp terminals, a yieldable contact carried by said block engaging the adjacent lamp terminal, a contact carried by said block engaging the adjacent battery terminal, a yieldable bridging member carried by 115 the latter contact adapted to electrically connect the contacts, and a push button normally working in the larger portion of the key slot and having a reduced portion normally outside of the casing, said button 120 loosely engaging the bridging member and being laterally shiftable when depressed to engage the reduced portion thereof in the narrow portion of the key slot and lock the member in circuit-closing position. 125

8. A device of the class described comprising a metallic casing having a key slot therein, a battery in the casing having a terminal at its outer end electrically connected with the casing and having a terminal at its inner end, a lamp having one terminal spaced from the inner battery terminal and a terminal electrically connected with the casing, a block of insulating material interposed between the spaced battery and lamp terminals, a yieldable contact carried by said block engaging the adjacent lamp terminal, a contact carried by said block engaging the adjacent battery terminal, a yieldable bridging member carried by the latter contact adapted to electrically connect the contacts, a push button normally working in the larger portion of the key slot and having a reduced portion normally outside of the casing, said button loosely engaging the bridging member and being laterally shiftable when depressed to engage the reduced portion thereof in the narrow portion of the key slot and lock the member in circuit-closing position, and means, for insulating the inner end of the button from the bridging member.

9. A device of the class described comprising a metallic casing having a key slot 30 therein and an internal rib opposite said slot, a battery in the casing having a terminal at its outer end connected with the casing and having a terminal at its inner end, a lamp having a terminal connected with the casing and a terminal spaced from the inner battery terminal, a removable block 35 of insulating material interposed between the spaced battery and lamp terminals and having a notch in one edge in which the rib on the casing engages and a cut-away portion opposite said notch, a yieldable contact carried by said block engaging the adjacent lamp terminal, a contact held to the opposite side of said block engaging the adjacent battery terminal, a yieldable bridging member carried by the latter contact 40 and extending through the cut-away portion of the block adapted to connect the contacts, a push button normally working in the larger portion of the key slot and having a reduced portion normally outside the casing, a flat spring held to the inner side 45 of the casing having a slot therein, and a stud of insulating material on the inner end of the button extending through said slot and loosely engaging the bridging member, said button being laterally shiftable when depressed to engage the reduced portion thereof in the narrow portion of the key slot.

10. A device of the class described comprising a metallic casing having a key slot 60 therein and an internal rib opposite said slot, a battery in the casing having a terminal at its outer end connected with the casing and having a terminal at its inner end, a lamp having a terminal connected with the casing and a terminal spaced from the inner battery terminal, a removable block of

insulating material interposed between the spaced battery and lamp terminals and having a notch in one edge in which the rib on the casing engages and a cut-away portion opposite said notch, a yieldable contact carried by said block engaging the adjacent lamp terminal, a contact held to the opposite side of said block engaging the adjacent battery terminal, a yieldable bridging member carried by the latter contact and extending through the cut-away portion of the block adapted to connect the contacts, a push button normally working in the larger portion of the key slot and having a reduced portion normally outside the casing, 80 and a stud of insulating material on the inner end of the button loosely engaging the bridging member, said button being laterally shiftable when depressed to engage the reduced portion thereof in the narrow portion of the key slot.

11. A device of the class described comprising a metallic casing having a key slot therein and an internal rib opposite said slot, a battery in the casing having a terminal at its outer end connected with the casing and having a terminal at its inner end, a lamp having a terminal connected with the casing and a terminal spaced from the inner battery terminal, a removable block 95 of insulating material interposed between the spaced battery and lamp terminals and having a notch in one edge in which the rib on the casing engages and a cut-away portion opposite said notch, a yieldable contact carried by said block engaging the adjacent lamp terminal, a contact held to the opposite side of said block engaging the adjacent battery terminal, a yieldable bridging member carried by the latter contact 100 and extending through the cut-away portion of the block adapted to connect the contacts, a push button normally working in the larger portion of the key slot and having a reduced portion normally outside the casing, a flat spring held to the inner side 105 of the casing having a slot therein, and a stud of insulating material on the inner end of the button extending through said slot and loosely engaging the bridging member, said button being laterally shiftable when depressed to engage the reduced portion thereof in the narrow portion of the key slot.

12. In a portable electric lighting device, 120 the combination of a metallic casing, a battery loosely held in the casing having terminals at opposite ends thereof, means carried by the casing at one end thereof frictionally engaging one battery terminal to electrically connect said terminal with the casing, a metallic lamp support detachably held to the other end of the casing, a lamp carried by said support having one terminal spaced from the adjacent battery terminal and one 125 130

terminal in circuit with said support, a push button extending through the casing formed with an abutment adapted to engage the inner side of the casing to limit the outward movement of the button, a pin of insulating material held to the inner end of the button, a spring held to the inner wall of the casing for normally forcing the button outwardly, said spring having an aperture through which said pin extends, a block of insulating material removably supported in the casing between the lamp and battery, contacts carried by said block engaging the adjacent battery and lamp terminals, and a yieldable circuit-closing member carried by said block and loosely engaged by said pin for electrically connecting the contacts when the button is forced inwardly.

13. In a portable electric lighting device, the combination of a metallic casing, a battery loosely held in the casing having terminals at opposite ends thereof, means carried by the casing at one end thereof frictionally engaging one battery terminal to electrically connect said terminal with the casing, a metallic lamp support detachably held to the other end of the casing, a lamp carried by said support having one terminal spaced from the adjacent battery terminal and one terminal in circuit with said support, a push button extending through the casing formed with an abutment adapted to engage the inner side of the casing to limit the outward movement of the button, a pin of insulating material held to the inner end of the button, a spring held to the inner wall of the casing for normally forcing the button outwardly, said spring having an aperture through which said pin extends, a block of insulating material removably supported in the casing between the lamp and battery, contacts carried by said block engaging the adjacent battery and lamp terminals, a yieldable circuit-closing member carried by said block and loosely engaged by said pin for electrically connecting the contacts when the button is forced inwardly, and co-operating means on the casing and block for alining the circuit-closing member with said pin.

14. In a portable electric lighting device, the combination of a metallic casing, a battery loosely held in the casing having terminals at opposite ends thereof, means carried by the casing at one end thereof frictionally engaging one battery terminal to electrically connect said terminal with the casing, a metallic lamp support detachably held to the other end of the casing, a lamp carried by said support having one terminal spaced from the adjacent battery terminal and one terminal in circuit with said support, a push button extending through the casing formed with an abutment adapted to engage the in-

ner side of the casing to limit the outward movement of the button, a pin of insulating material held to the inner end of the button, a spring held to the inner wall of the casing for normally forcing the button outwardly, said spring having an aperture through which said pin extends, a block of insulating material removably supported in the casing between the lamp and battery, contacts carried by said block engaging the adjacent battery and lamp terminals, and a yieldable circuit-closing member carried by said block and loosely engaged by said pin for electrically connecting the contacts when the button is forced inwardly, the casing being formed with an internal projection and the block with a recess in which said projection engages for maintaining the circuit-closing member in register with the push button.

15. A device of the class described comprising a metallic casing having a key slot 85 therein, a lamp having one terminal connected with the casing, a battery in the casing having one terminal connected with the casing, circuit-closing means held against rotation in the casing including a flexible metallic bridging member adapted to be pressed inwardly to complete the lamp circuit, and a push button for pressing said member inwardly normally extending through the larger portion of the key slot in the casing 95 and having a reduced shank portion normally outside the casing, said button slidably engaging the outer side of said member and being shiftable laterally relatively to the member while in contact therewith when depressed to permit the reduced shank of the button to be passed sidewise into the narrow portion of the key-slot.

16. A flash-light comprising a tubular battery-inclosing casing, a combined reflector and lamp socket having its outer edge of greater diameter than the casing and bent back upon the convex side of the reflector to form an annular flange spaced from the outer side of the reflector, and a lens-holding ring concentric with said flange having an inwardly extending flange overhanging the outer end of the reflector to clamp a lens against the outer end of the reflector, said ring and the reflector flange 110 being provided with means forming a bayonet joint connection therebetween, and said reflector being provided with a tubular extension at the convex side thereof of less diameter than the outer end of the reflector 120 frictionally held to one end of the battery-inclosing casing.

In testimony whereof I hereunto affix my signature.

CHARLES WACHTEL
